COMBINATION STATUE AND LAMP

Nathan Lichtenstein and Peter Di Matteo,
Brooklyn, N. Y.

Application December 14, 1949, Serial No. 6,627

Term of patent 14 years

(Cl. D48—20)

To all whom it may concern:

Be it known that we, Nathan Lichtenstein and Peter Di Matteo, respectively, a citizen of the United States of America, residing in the Borough of Brooklyn, Kings County, in the city and State of New York, and a citizen of the United States of America, residing in the Borough of Brooklyn, Kings County, in the city and State of New York, have invented a new, original, and ornamental Design for Combination Statue and Lamp, of which the following is a specification, reference being had to the accompanying drawings, forming a part hereof, in which—

Fig. 1 is a front elevation of a combination statue and lamp, showing our new design.

Fig. 2 is a rear perspective view thereof; and

Fig. 3 is a top perspective view partly in section taken on the line 3—3 of Fig. 1.

The dotted lines shown in the drawing are for illustrative purposes only.

We claim:

The ornamental design for a combination statue and lamp, substantially as shown and described.

NATHAN LICHTENSTEIN.
PETER DI MATTEO.
